US00D462215S

(12) **United States Design Patent** (10) Patent No.: **US D462,215 S**
 Bartelt et al. (45) Date of Patent: ** Sep. 3, 2002

(54) **DISPENSER**

(75) Inventors: **Linda Louise Bartelt**, Winneconne, WI (US); **Cherry Ann Bochmann**, Cleveland, OH (US); **William Robert Newman**, Neenah, WI (US); **Craig Martin Saunders**, Rocky River, OH (US); **Herb F. Velazquez**, Neenah, WI (US)

(73) Assignee: **Kimberly-Clark Worldwide, Inc.**, Neenah, WI (US)

(**) Term: **14 Years**

(21) Appl. No.: **29/129,313**

(22) Filed: **Sep. 12, 2000**

(51) LOC (7) Cl. **20-02**

(52) U.S. Cl. **D6/519**; D6/545

(58) Field of Search D6/515, 518, 519, D6/520, 523, 542, 545; 206/77.1, 389, 391; 211/13.1; 221/45, 282; 222/105, 173, 180; 242/558, 560, 570, 590, 595, 598

(74) Attorney, Agent, or Firm—Brinks Hofer Gilson & Lione

(57) **CLAIM**

The ornamental design for a dispenser, as shown and described.

DESCRIPTION

FIG. 1 is a front elevational view of a dispenser showing our new design;

FIG. 2 is a left side elevational view thereof;

FIG. 3 is a rear elevational view thereof;

FIG. 4 is a top, front, and left side perspective view thereof;

FIG. 5 is a right side elevational view thereof; and,

FIG. 6 is a top plan view thereof.

The broken-line disclosure is for illustrative purposes only and forms no part of the claimed design.

1 Claim, 6 Drawing Sheets
